(57) **CLAIM**

The ornamental design for a power station inverter for electric vehicle charging as shown and described.

DESCRIPTION

FIG. 1 is a front left perspective view of a power station inverter for electric vehicle charging showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the power station inverter for electric vehicle charging showing that form no part of the claimed design.
